UNITED STATES PATENT OFFICE.

JOHN H. STEWART AND JOHN M. SCHENK, OF WATERLOO, IOWA, ASSIGNEES TO CEMENT TILE MACHINERY COMPANY, OF WATERLOO, IOWA.

TILE-MACHINE.

No. 927,895.

Specification of Letters Patent.

Patented July 13, 1909.

Application filed August 14, 1908. Serial No. 448,502.

To all whom it may concern:

Be it known that we, JOHN H. STEWART and JOHN M. SCHENK, citizens of the United States of America, and residents of Waterloo, Blackhawk county, Iowa, have invented certain new and useful Improvements in Tile-Machines, of which the following is a specification.

Our invention relates to improvements in tile-machines, and the object of our improvement is to provide a rotatable former-head adapted to coöperate with an exterior mold in forming a tile from concrete or similar materials, the portions of such head which are most subject to wear being adapted for adjustment to compensate for loss occasioned by such wear, and being formed of such material as is most resistant to loss by wear. This object we have accomplished by the means which are hereinafter fully described and claimed, and which are illustrated in the accompanying drawings, in which:

Figure 1 is a side elevation of our improved former-head, showing it within and spaced away from a hollow cylindrical mold. Fig. 2 is another elevation of said former-head, with portions broken away to disclose the interior, in part, taken at an angle of ninety degrees from the point of view in Fig. 1. Fig. 3 is a detail view, showing the upper part of the head with its connections and seats for the intermediate parts. Fig. 4 is another view of the parts shown in Fig. 3, taken at an angle of ninety degrees from the latter. Fig. 5 is a horizontal section of Fig. 3 on the line *c-d* of the latter. Fig. 6 is an under plan view of the structure depicted in Fig. 4. Fig. 7 is a horizontal section, enlarged, of the former-head shown in Fig. 1, taken along the line *a-b* of Fig. 1. Fig. 8 is a perspective of one of the intermediate adjusting-plates. Fig. 9 is a perspective of one of the intermediate outer forming-plates. Fig. 10 is a perspective of said plates combined.

Similar numbers refer to similar parts throughout the several views.

The hollow cylindrical mold-casing 3 is adapted to receive the former-head 8, and is spaced away from same concentrically to a distance equal to the determined thickness of the tile to be formed, therebetween. The former is movable through said mold-casing, but it is wholly immaterial whether the

former be moved longitudinally through the casing, or the casing be moved longitudinally over the former. The upper portion 2 of the former is of a substantially conical or bell-shape, with a cylindrical upper extension 60 having an interiorly-threaded seat 24 for the threaded shank 23 of a rotatable shaft 1, and the latter may be rotated by means of any suitable source of power. The intermediate removable and adjustable plates 5, which 65 continue the outer contour of the bell-like form, downward, are succeeded in line below by the cylindrical head 8. The parts 5 and 8 taken together are exteriorly bell-shaped as stated, but have on opposite sides 70 depressions 26. The depressions 26 have one vertical abrupt angular edge 27 adjacent to the deepest part thereof, while the opposite side of each depression as well as of their extensions 4, shade off more shallowly and 75 gradually tangentially with the bell-surface of the parts. The exterior form of this modeling body has been patented under United States Patent Number 819,931, issued to John M. Schenk and Joseph Schenk, on 80 May 8th, 1906, and it is our intention by our present invention to not claim this special form of modeling-head, but merely the construction of such a head whereby its parts which are subject to peripheral wear may be 85 adjusted at will to keep the outer form true, and thus insure longer operative efficiency for it. With this latter idea in view, we form the intermediate plates 5 of steel or hardened iron to insure long wearing efficiency, and arrange for adjusting the radial position of each plate independently of each other so as to allow for loss caused by friction of the outer contact-surface of each while in 90 operation. The shank 2 has a centrally located depending plate 12 whose vertical edges are well within the outer lower edge of such shank, and whose lower corners are rounded and recede inwardly toward a fillet or flange 13 integral with said plate and concentric with the shaft 1. The fillet 13 has at 95 opposite sides lugs which are vertically oriented to receive the lower ends of the pins 11, other orifices or sockets 10 being provided in the overhanging lower surface of the shank 2 in line to receive the upper ends of said pins, for a purpose to be hereinafter described. A central exteriorly-threaded projection 9 depends from the plate 12 and is adapted to 100 screw into an interiorly-threaded central 105 screw 15. The shank 2 has a shoulder 16 at its upper end, and a shoulder 17 at its lower end, the shoulder 17 being 110

opening 25 in the top of the cylindrical former 8.

The numeral 6 designates a spacing-block adapted to be seated intermediately between each outer plate 5 and the depending plate 12. Each block 6 is removably and pivotally secured to the shank 2 and fillet 13 by means of one of the pins 11 inserted in its vertical orifice 20. As shown in Fig. 7, each 10 vertical curved ridge in which the orifice 20 is located is adapted to move or rock in the curved hollow between the curved vertical ridge 28 on the plate 12 and its radial extension. The plate 6 has its exterior face so 15 curved as to closely fit against the inner face of the plate 5 along the greater portion of its extent, but a portion of the block or plate 6 is exposed in the concavity 26 of the head for a certain purpose. The plate 5 is removably 20 secured to the block 6 by means of a machine-screw 7 entering registering threaded openings 22-21 in both parts.

Each exposed portion of the plates 6 has an orifice 15 large enough to receive not only 25 the stem but also the head of an adjusting-screw 16, and the latter works within a threaded opening 29 in the plate 12 and extends therethrough into a plain socket 18 in the oppositely-placed plate 6. A contact-plate 17 is seated on the end of the screw 16 in a groove thereon so that the latter may move relatively to said plate, the plate bearing against the inner surface of each plate 6 opposite to the end of said plate 35 which has an orifice 15. The head of the screw 16 may be provided with a transverse slot for a screw-driver, or the head may be hexagonal, the opening 15 being large enough to admit a socket-wrench with which 40 to engage the head.

The plates 5, when secured to the plates 6 as above described, are not again disassembled until worn out.

When it is desired to adjust the plates 5 45 outwardly a sufficient distance to compensate for wear of their outer contact surfaces, the screws 16 may be turned which forces such plates outward with their carrying-blocks 6. It is obvious that the adjustment 50 of the former-head may thus be effected at any time, when the machine is stopped, without removing the head from the shaft 1.

The former-head shown may be moved 55 vertically through the casing 3 by any desired means, and rotated simultaneously, the conical part of the head and the depressions 26 serving to draw down the material supplied from above, while the cylindrical base 8 packs the material and compresses it 60 against the casing 3 in a well-known manner.

Having described our invention, what we

claim as new, and desire to secure by Letters Patent, is:

1. In a tile machine, a former-head composed of a supporting body, a cylinder detachably secured to the free end of said body, an intermediate plate detachably secured to said supporting body and radially adjustable, and an outer plate detachably secured upon the outer side of said intermediate plate. 65

2. In a tile machine, a former-head composed of a supporting body, a cylindrical former detachably secured to the free end thereof, intermediate plates detachably and 75 adjustably secured to said supporting body, and an outer contact-plate detachably secured to each of said intermediate plates.

3. In a tile machine, a former-head of an approximately bell-shaped form and having 80 a depending hanger, a forming cylinder detachably secured to said hanger, intermediate adjusting-means detachably secured to said hanger, and contact-plates detachably secured to said adjusting-means between 85 said supporting body and said cylindrical former.

4. In a tile machine, the combination with an outer mold-casing, of a rotatable former-head therein and spaced apart therefrom, 90 said former-head being composed of a substantially bell-shaped head furnished with oppositely-located depressions and having a depending hanger, a cylindrical former detachably secured to said hanger, detachable 95 spacing-plates pivotally secured to opposite sides of said hanger between said head and said cylindrical former, means for separately adjusting said spacing-plates to vary the distance of one part thereof from said hanger toward said mold-casing, and a contact-plate detachably secured to the outer side of each of said spacing-plates with an outer surface continuing the outer control 100 of the adjacent part of said head. 105

5. In a tile machine, the combination with an outer mold-casing, of a former-head adapted to operate therein composed of a core, a spacing-plate on each side of said core and detachably connected thereto, a 110 forming-plate detachably secured to the outer side of each spacing-plate, and adjusting-means adapted to separately vary the distance of such spacing-means from said core to permit of keeping the outer wearing 115 periphery of said forming-plates in a determined distance from the axis of the core.

Signed at Waterloo, Iowa, this 27th day of July, 1908.

JOHN H. STEWART.
JOHN M. SCHENK.
